UNITED STATES PATENT OFFICE

2,114,823

CONTAINER

Louis P. Toscano, Brooklyn, N. Y.

Application January 22, 1937, Serial No. 121,803

5 Claims. (Cl. 229—43)

This invention relates to improvements in containers, and more particularly to a cover therefor.

In the dispensing of foodstuffs or beverages in sealed cardboard containers having removable covers, difficulty is experienced in the application of the cover to the container body and later during its removal therefrom. This condition is caused by the absence of an air vent in the container, for upon application of the cover, air 10 must be expelled from within the container while a vacuum condition within the container occurs when an attempt is made to remove the cover. Such condition is annoying to the users of such cardboard containers and sometimes results in 15 spillage of the contents of the container. It is a custom of users of such containers to overcome the above condition to puncture the cover by the use of an ice pick, fork, or other implement which might be at hand, but such practice is not sanitary, and often results in the punching of holes 20 too large as to admit foreign matter into the container, permitting escape of the aromas of the container contents, and permitting leakage of the contents therefrom.

It is therefore, one of the objects of this invention to provide an air vent in the container cover which facilitates ease of application of the cover to the container body and of its removal therefrom, and which prevents the leakage of the 25 contents and the aromas thereof from the container and the accidental entrance of foreign matter thereinto through the air vent.

Another important feature of the invention is to provide a multiple flap vent in the paper cover 30 of a container to enable the free passage of air from the container during the application of the cover and which causes the gradual closing of the vent by the multiple flaps to maintain the aromas of the contents within the container and 35 to prevent spillage of the contents should the same be a liquid.

Another feature of the invention resides in a 40 cardboard container cover which includes a shielded vent which may be formed therein during formation of the cover without extra cost of manufacture.

Other objects of the invention will be apparent as the following specification is read in conjunction with the accompanying drawing, in which: 50 Figure 1 is a perspective view of my improved cardboard container.

Figure 2 is an enlarged detail vertical sectional view on the line 2—2 of Figure 1.

Figure 3 is a fragmentary top plan view of the 55 central portion of the removable cover.

Referring to the drawing by reference characters, the numeral 10 designates my improved container in its entirety, and which includes a cylindrical body 11 having a bottom wall and being open at its top. The body 11 may be constructed of cardboard which is so formed and treated as to be waterproof. However, the container may be of any other material or combinations of material if desired.

Fitting over the open top of the body 11 is 10 a round cover 12 constructed of cardboard or like fibrous material and treated to be waterproof. The cover 12 includes a disk top wall 13, the periphery of which is rolled up and interlocked with the inwardly rolled bead 14 provided on the 15 annular depending side wall 15 and which side wall is of a diameter to snugly telescope the exterior of the side wall of the container body 11.

The top wall 13 of the cover 12 is provided with two opposed arcuate shaped slits 16—16, 20 there being relatively short uncut portions 17—17 therebetween, as best seen in Figure 3 of the drawing. The arcuate slits 16 are preferably disposed axially of the disk top wall 13 and may be formed by means of a punch die which bends or punches inwardly, the material disposed inwardly of the slits 16, the line of bend or fold being parallel to an imaginary line drawn between the uncut portions 17—17. The inwardly punched portions constitute two semi-circular shaped flaps 18—18 disposed in normally downwardly outwardly diverging relation, as best seen in Figure 2. Normally the flaps 18 just clear the walls of the openings 19—19 which openings are formed when the flaps are punched inwardly and in use 25 they act to substantially close the openings against the escape of aromas or spillage of the contents from the container body, and prevent the accidental entry of foreign matter into the container body.

In practice, assume that the cover 12 is separated from the container body 11, and the container is to be used in the dispensing of foodstuffs or beverages, be they hot or cold. The foodstuff or beverage is placed into the container body 11 and the cover 12 applied over the open top thereof. By reason of the openings 19—19, any excess air trapped between the top of the cover and the top of the contents of the container body as the cover is applied will be gradually exhausted 30 therethrough. By reason of the gradual exhaust of the air within the container as the cover is applied, and the accumulation of any gases within the container from the contents thereof, will cause the flaps 18 to bend outwardly and assume 35 40 45 50 55 60 65 70 75 80 85 90 95 100

a plane flush with the top wall 13, thus substantially closing the openings 19-19. This enables the cover to freely telescope the container body. Assume that the cover is to be removed from the 5 container body, it is apparent that as the cover is moved outwardly, a vacuum occurs within the container causing the flaps to bend inwardly and permit atmospheric air to enter through the openings 19-19, thus permitting free removal of the cover. As previously stated, the flaps 18-18 act to shield the contents of the container against spillage and against the entry of foreign matter through the openings 19-19, the said flaps acting more or less in the capacity of flap valves for the respective openings.

While I have shown and described what I consider to be the most practical embodiment of my invention, I wish it to be understood that such changes or modifications as come within the scope of the appended claims may be resorted to if desired without departing from the spirit of the invention; that the vent may be made such as to have one, two or any number of prongs desired.

Having thus described the invention, what I claim as new and desire to secure by Letters Patent of the United States, is:—

1. A container comprising in combination, a body open at its top, a paper cover having an air vent in the top thereof, and means formed from the top of said cover and normally extending inwardly thereof for substantially closing said

air vent upon application of said cover to said body.

2. A container comprising in combination, a body open at its top, a paper cover snugly telescoping the open top of said body and having an air vent opening punched inwardly through the top thereof, and closure means for said vent opening formed by the normally inwardly extending material displaced in the punching of the air vent opening.

3. A container comprising in combination a cylindrical body open at its top, a round paper cover snugly telescoping the open top of said cylindrical cover, and a flap punched inwardly from the top of said cover to form an air vent opening 15 therein and a closure therefor.

4. A container comprising in combination, a cylindrical body open at its top, a round paper cover snugly telescoping the open top of said cylindrical cover, a pair of flexible normally inwardly extending outwardly diverging flaps punched inwardly from the central portion of the top of said cover and providing air vent openings therein.

5. A removable cover for open containers comprising a paper diaphragm, a pair of flexible normally inwardly extending outwardly diverging flaps punched from said diaphragm to initially provide vent openings therein and to subsequently act to close said vent openings after application 25 of the cover to a container.

LOUIS P. TOSCANO.
